UNITED STATES PATENT OFFICE

107,646

DESIGN FOR A COMBINATION LAMP, SHADE, AND RADIO

Joseph J. Herrera, Jr., Los Angeles, Calif.

Application February 9, 1937, Serial No. 67,539

Term of patent 3½ years

To all whom it may concern:

Be it known that I, Joseph J. Herrera, Jr., a citizen of the United States of America, residing at Los Angeles, in the county of Los Angeles and State of California, have invented a new, original, and ornamental Design for a Combination Lamp, Shade, and Radio, of which the following is a specification, reference being had to the accompanying drawing, forming a part thereof.

Fig. 1 is a perspective view of the combination lamp, shade, and radio, showing my new design;

Fig. 2 is an inverted bottom view of Fig. 1;

Fig. 3 is a side elevation, further illustrating my new design.

I claim:—

The ornamental design for a combination lamp, shade, and radio substantially as shown.

JOSEPH J. HERRERA, JR.
